(No Model.)

F. P. KREWSON.
MACHINE FOR PULVERIZING SOIL.

No. 593,848.

Patented Nov. 16, 1897.

UNITED STATES PATENT OFFICE.

FRANKLIN PIERCE KREWSON, OF PHILADELPHIA, PENNSYLVANIA.

MACHINE FOR PULVERIZING SOIL.

SPECIFICATION forming part of Letters Patent No. 593,848, dated November 16, 1897.

Application filed April 25, 1896. Serial No. 588,999. (No model.)

To all whom it may concern:

Be it known that I, FRANKLIN PIERCE KREWSON, a citizen of the United States, and a resident of Philadelphia, (Frankford,) in the county of Philadelphia and State of Pennsylvania, have invented certain new and useful Improvements in Machines for Pulverizing Soil, of which the following is a specification, reference being had to the accompanying drawings, forming a part thereof, in which similar letters of reference indicate corresponding parts.

This invention relates to machines for pulverizing soil and to that class thereof known as "harrows;" and the object of the invention is to provide an improved device of this class whereby the soil or the clods may be thoroughly pulverized and crushed and the ground leveled without going over the same more than once; and with these and other objects in view the invention consists in the construction, combination, and arrangement of parts hereinafter described and claimed.

My improved pulverizing-machine involves a frame in which are mounted two rollers, said rollers being arranged diagonally in or below said frame or at an angle to a longitudinal line passing therethrough, and said rollers are provided with teeth in the usual manner, which are designed to break up and thoroughly pulverize the soil.

The invention is fully disclosed in the following specification, of which the accompanying drawings form a part, in which—

Figure 1 is a side view of my improved pulverizer; Fig. 2, a plan view thereof; Fig. 3, a plan view of an attachment by which the inner ends of the rollers are supported; Fig. 4, a side and an edge view thereof, part of the construction in the edge view being shown in section; Fig. 5, a sectional detail of the construction, and Fig. 7 a side view of a part of the frame.

In the practice of my invention I provide a frame which comprises two similar rectangular sections A and B, which are hinged together at C and which are adapted to be folded together, and I also provide plates or strips E, which are secured, when the machine is in use, to the sides of the frame across the hinged connections thereof, so as to stiffen and support said frame, and these strips or

plates may be secured in position by bolts E² or in any desired manner, and the frame may be provided with corresponding slots or grooves, in which the strips or plates are placed. At the opposite sides of the separate sections of the frame are secured hangers D, and suspended centrally of the frame or from the side of one of the sections thereof is another hanger G, a plan view of which is shown in Fig. 3 and a side and edge view in Fig. 4.

The hanger G is provided at its lower end with a head g, in the opposite sides of which are formed cavities or recesses g², said cavities or recesses being yoke-shaped in form at their lower sides and being provided with cross bars or bolts g³, and the lower inner portions of said cavities or recesses are spherical in form, and the hanger H is suspended from the frame by means of bolts or other devices which pass through a longitudinal slot H, formed in one side of one of the sections of the frame, and the position thereof may be adjusted forwardly or backwardly by a bolt h, which passes into the upper end thereof, and a head h² of which projects at the rear side of the frame, said hanger being provided with a cross-head h³, into which passes a set-screw h⁴.

Mounted in the hangers D and G are shafts K, the inner ends of which are secured in sockets k, which are provided with circular heads and adapted to enter the circular cavities or recesses g² in the lower end of the hanger G, and the outer ends of these shafts are also pivotally connected with the lower ends of the hangers D in any desired manner, this connection being preferably the same as that between the shafts and the central hanger G, and the object of this construction being to provide means whereby the angle of such shafts may be changed within certain limits when desired.

Mounted on each of the shafts K is a roller M, the body portion of which may be of any desired construction, and said roller preferably consists of a plurality of staves m, which are secured to a suitable framework, consisting of annular bands m², which are connected with the shafts by spokes m³, and each of the staves m is provided with a row of teeth m⁴, which are secured therein, as shown in Fig. 6, but which may be connected therewith in

- any desired manner. These teeth are similar to the usual harrow-teeth, and any desired number thereof may be employed. I also provide a detachable tongue or pole O, which 5 may be connected with the frame in any desired manner and which is provided with a seat O², and pivotally connected with the forward part of the frame at O³ are rods or braces O⁴, which are connected with a tongue 10 or pole at O⁵, and the usual doubletree O⁶ and singletrees O⁷ are also provided, and the doubletree O⁶ is connected with the pivotal support of the rods or braces O⁴ at O⁸ by means of chains O⁹.
- 15 The operation will be readily understood from the foregoing description when taken in connection with the accompanying drawings and the following statement thereof. The position of the rollers M is such that while they 20 revolve in the usual manner there is also a dragging or sliding motion thereof, and the arrangement of the teeth m⁴ is such (said teeth being arranged in longitudinal and transverse and circular rows) that every particle of the 25 soil over which they pass is brought in contact therewith, and because of this motion of the rollers the soil is finely divided and the ground leveled off at the same time, and it will also be observed that because of the in- 30 clination or angular position of the rollers a greater width of ground is covered thereby than would be possible if said rollers were arranged in direct line, as usual in this class of devices.
- 35 This machine or pulverizer may be drawn by a single pair of horses in the usual manner, and it is evident that changes in and modifications of the construction herein described may be made without departing from 40 the spirit of my invention or sacrificing its advantages, and I reserve the right to make all such alterations therein and modifications

thereof as fairly come within the scope of the invention.

Having fully described my invention, I 45 claim as new and desire to secure by Letters Patent—

The herein-described harrow comprising a frame in which are mounted two rollers which are provided on their outer surfaces with 50 spikes or teeth, said rollers being suspended by hangers which are connected with said frame, two of which are arranged at the opposite side thereof, and one at the center and a little to the rear of the other two, and said 55 rollers being each mounted on separate shafts, the inner ends of which are connected with the central hanger by a ball-and-socket or pivotal joint and the outer ends of said shafts being pivotally connected to their respective 60 hangers by means of an opening in said hangers, through which the ends of the said shafts project, and in which they have a sliding play, whereby the said rollers are held at an angle to the longitudinal line of said frame, 65 and the position of the central hanger being transversely adjustable, and said frame being composed of two separate sections which are hinged together, and being also provided with means whereby when in use, the separate 70 frames may be rigidly connected, and said frame being also provided with a tongue or pole which is connected with the frame transversely thereof, all substantially as shown and described, and for the purpose set 75 forth.

In testimony that I claim the foregoing as my invention I have signed my name, in presence of the subscribing witnesses, this 21st day of April, 1896.

FRANKLIN PIERCE KREWSON.
